UNITED STATES PATENT OFFICE.

HARRY W. HILL, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

DESIGN FOR A BLANK FOR AN OPHTHALMIC LENS.

59,747.

Specification for Design.

Patented Nov. 22, 1921.

Application filed November 27, 1920. Serial No. 426,816. Term of patent 14 years.

To all whom it may concern:

Be it known that HARRY W. HILL, a citizen of the United States, residing at Southbridge, in the county of Worcester and State of Massachusetts, have invented a new and original, ornamental Design for a Blank for an Ophthalmic Lens, of which the following is a specification, reference being made to the accompanying drawings, forming a part thereof.

In the drawing I have illustrated a blank for an ophthalmic lens embodying my design. It will be noted that I have shown the blank in full or half lines accompanied by a dotted line border upon three sides. This is for the reason that the blank may be either so cut, molded or otherwise shaped in my improved design as to give the novel and improved appearance as illustrated by the half blank lines, or the same may be formed with an ordinary cutter and crumbed off, when it will have substantially

the appearance indicated by the dotted lines, due to the slightly uneven breakage of the glass in separation.

I would invite particular attention to the substantially triangular shape or design of my improved lens or lens blank, in which the several sides of the triangle are formed by intersecting or merging curves; also to the fact that the blank is provided with an outer edge and a central dividing line portion, which parts are concentric one with the other.

I claim:

The ornamental design for a blank for an ophthalmic lens substantially as shown and described.

In testimony whereof I affix my signature in the presence of two witnesses.

HARRY W. HILL.

Witnesses:

ALICE G. HASKELL,
ESTHER M. LAFLER.
